UNITED STATES PATENT OFFICE.

FLOYD L. INGRAHAM, OF PHILADELPHIA, PENNSYLVANIA, ASSIGNOR, BY MESNE ASSIGNMENTS, TO RAILWAY JOURNAL PACKING COMPANY, INC., A CORPORATION OF NEW YORK.

PACKING FOR JOURNAL-BOXES.

1,279,700.

Specification of Letters Patent. Patented Sept. 24, 1918.

No Drawing.

Application filed March 8, 1917. Serial No. 153,444.

To all whom it may concern:

Be it known that I, FLOYD L. INGRAHAM, a citizen of the United States, residing in Philadelphia, Pennsylvania, have invented 5 certain Improvements in Packing for Journal-Boxes, of which the following is a specification.

One object of my invention is to improve the packing used in journal boxes, particularly car axle boxes, in which the lubricating oil is conveyed to the journal by waste, usually of wool, or a similar textile material.

Another object of the invention is to provide means for opening up the mass of wool 10 waste to give it resiliency so as to enable the fiber to more readily carry the oil from the lower portion of the box to the journal.

In carrying out my invention, I preferably mix the waste, of wool, cotton, or similar fibrous material, with a seaweed, or marine grass, and the particular marine grass that I have used is known as eel grass (*Zoster* 20 *marrina*). I find that this grass has a considerable amount of elasticity and will not readily take up the lubricating oils used so that when this grass is thoroughly mixed with the fibers of the waste, the waste is forced against the journal and will readily convey the lubricating oils from the lower 25 portion of the box to the journal.

In preparing the packing, I preferably pass the waste through a combing machine, which will open up the fibers and remove the dirt, or other foreign material, from the

waste, and at the same time I introduce 35 strands of seaweed, in given proportions, to this waste, and, as the seaweed is dry, the greater portion of the sand adhering thereto has dropped away and this additional agitation removes the sand that still remains on 40 the grass as it is mixed with the waste and also removes any salt crystals that may be present on the seaweed so that when the packing is ready for insertion in a journal box it is free of dirt and sand. 45

While I prefer to use wool waste, it will be understood that a combination of wool and cotton may be used, and, in some instances, cotton may be used alone, but I prefer, where possible, to use a waste in which 50 the wool is in excess.

The eel grass which I prefer to use has the property of not absorbing the lubricating oils to any appreciable extent and retains its resiliency for a long time so that it is especially applicable for use in journal boxes and particularly car axle boxes. 55

I claim:

1. A fibrous packing for journal boxes consisting of a textile waste combined with 60 eel grass.

2. A packing for journal boxes consisting of wool waste thoroughly mixed with an eel grass from which the sand, and other foreign matter adhering thereto, has been removed. 65

In witness whereof I affix my signature.

FLOYD L. INGRAHAM.
